UNITED STATES PATENT OFFICE.

JOSEPH GOULDBOURN, OF LEICESTER, ENGLAND, ASSIGNOR TO UNITED SHOE MANUFACTURING CORPORATION, OF PATERSON, NEW JERSEY, A CORPORATION OF NEW JERSEY.

MACHINE FOR INSERTING FASTENINGS.

Application filed June 18, 1920. Serial No. 389,869.

To all whom it may concern:

Be it known that I, JOSEPH GOULDBOURN, a subject of the King of England, and resident of Leicester, Leicestershire, England, 5 have invented certain Improvements in Machines for Inserting Fastenings, of which the following description, in connection with the accompanying drawings, is a specification, like reference characters on the drawings indicating like parts in the several figures.

This invention relates to machines for inserting fastenings. By way of illustration, the invention is herein shown as embodied 15 in a machine for inserting screw threaded fastenings in the soles of boots and shoes, of the type disclosed in United States Letters Patent No. 490,621, granted Jan. 24, 1893, on an application of Louis Goddu.

20 In the use of such machines on some kinds of work, it is required that fastenings shall be spaced from each other by distances greater than those obtainable by machines constructed as in said Letters Patent. In 25 such cases, the operator was required to advance the work manually between successive fastening locations, thus increasing the laboriousness of the insertion of the fastenings and considerably reducing the output 30 of the machine.

In order to obviate these disadvantages, mechanism of the character shown and described in Letters Patent No. 1,264,188, granted April 30, 1918 to A. E. Jerram and 35 J. Gouldbourn was devised, by the use of which the machine may, at the will of the operator, readily be rendered capable of inserting fastenings at wider spacings than those provided for by the normal range of 40 feed of the work by the machine. When such mechanism is incorporated in the machine spacings of the fastenings outside the normal range of the machine may be obtained by suspending automatically the operation of the fastening inserting mechanism 45 once between each two fastening insertions, so that as long as extra wide spacing is desired, the work feeding mechanism will impart to the work two work feeding movements between every two fastening inserting 50 operations, thereby doubling the spacing range of the machine.

It is desirable, in operating on certain

classes of work, that the spacings of the fastenings shall vary in different parts of a single piece. For example, in the manufacture of certain classes of shoes, the sole attaching nails may be inserted in the forepart of a shoe at considerably greater distances apart than in the shank without detracting materially from the strength or durability of the shoe. In such cases, equal spacing of the nails throughout would involve either a waste of fastening material and reduced output of the machine by reason of the insertion of an unnecessarily large number of nails in the forepart or a substantial weakening of the shoe due to the lack of a sufficient number of nails in the shank.

When mechanism of the kind shown in Letters Patent, No. 1,264,188, is employed to obtain extra wide spacings of fastenings in a portion of a piece of work, the output of the machine is necessarily restricted, since a plurality of work feeding operations is required to advance the work between successive fastening locations. Moreover, it is frequently desirable that the ratio between the shorter and longer spacings shall be other than the proportion of one to two.

It is an object of the invention to provide a novel mechanism adapted for use in a machine for inserting fastenings to enable the operator during operation of the machine to vary the normal feed of the work from one range to another, so as to cause fastenings to be inserted in the work at greater or less distances apart. Inasmuch as change to the wider spacings under the control of the mechanism is effected by varying the normal feed of the work, such change does not affect the rate of insertion of the fastenings. Consequently, the output of the machine under such conditions of operation is greater than when the extent of feeding movement of the work between successive fastening inserting operations is increased by suspending the operation of the fastening inserting mechanism, thereby multiplying the range of the work feeding movement. In the illustrated construction, the ranges of feeding movement are determined by stops, both of which are adjustable to enable the extent of both the smaller and the larger ranges of feed-

ing movement and the ratio between the respective ranges of feeding movement to be varied as desired.

A further feature of the invention resides in novel operating means for a work feeding device comprising an element for coupling together certain of its members, one of which is mounted for swinging movement on the frame of the machine, and means 10 acting on the element at the axis of swing of the member to change the point of connection of the members in order to vary the feed of the work. In consequence of this construction, swinging movement of the member does not move the element relatively to the member or affect the operative connection between the element and its actuating devices.

It is a further object of the invention to provide means for controlling the feed of the work which, in addition to the above-mentioned and other advantages, will possess all the advantages attendant upon the mechanism shown in Letters Patent, No. 1,264,188, particularly as regards adapting a fastening inserting machine to deal with spacings in excess of the normal range of spacings of the machine. Accordingly, the invention embodies mechanism for multiplying 20 integrally the range of feeding movement of the work between successive fastening inserting operations, distinct from the mechanism referred to above for varying the feed of the work in a different ratio. The invention, in one of its aspects, is further characterized by the provision of a common actuator for these mechanisms. Preferably, and as shown, the actuator is arranged for control by the operator through the agency 30 of a knee lever and has associated with it means for selectively connecting it to the respective mechanisms.

Other objects and features of the present invention will be apparent from the following detailed description of a machine of the type described having the present invention incorporated therein. It is to be understood, however, that the invention is not intended to be limited to use in connection 40 with machines of this type, since the applicability of the invention to fastening inserting machines of other types is recognized.

In the drawings:

Fig. 1 is a side elevation of a machine for inserting screw threaded fastenings embodying mechanism according to the invention;

Fig. 2 is a detail showing the means for periodically suspending the insertion of fastenings in operative position;

Fig. 3 is a view in front elevation, partly in section, showing the means for varying the normal range of feed of the work;

Fig. 4 is a view in elevation of the devices 60 for controlling the feed of the work;

Fig. 5 is a view in plan of the parts seen in Fig. 4.

The machine has a base carrying a column 2 which supports a head 4 having mounted therein a vertically disposed spindle 6 which carries the screw-threaded wire from which the fastenings are formed. The spindle 6 is continuously rotated by a belt passing over a pulley 8 on the upper end of the spindle and over idlers 10 to a driving pulley (not shown) in the base of the machine, arranged to be clutched to a continuously running pulley operated from a source of power. The spindle 6 is provided with a worm which engages worm gears 20 (Fig. 1) upon the forward ends of parallel shafts, one of which is indicated at 22, this shaft 22 carrying the various cams for effecting the wire feeding, wire severing, work feeding, and automatic horn depressing movements. These cams are each formed to cause two operations of the parts operated thereby during each complete revolution of the cam shaft 22.

The wire is fed downwardly, through the spindle 6 by a wire feeding and inserting sleeve 24 surrounding the spindle 6 and slidably mounted in guideways in the machine frame, the lower end of said sleeve being provided with wire gripping members 26 which operate intermittently to seize the wire as the sleeve is moved downwardly. The sleeve 24 is reciprocated in the machine frame to feed successive lengths of wire and insert them in the work by a wire feed lever 28 (Fig. 3) pivoted at 30 to the machine frame and having two forwardly projecting arms 31 each carrying a segmental gear 32, the gears 32 engaging respectively racks 34 formed on a yoke attached to the upper end of the sleeve 24. An upwardly extending arm 36 (Fig. 3) of the lever 28 carries a cam roll 38 operatively engaged by a wire feeding edge cam 40 on the cam shaft 22. The wire feed lever 28 is normally held in position to be operated by the cam 40 to move the wire feeding sleeve 24 downwardly by a comparatively strong spring (not shown) the lower part of which bears against a part of the lever 28.

After a proper length of wire has been inserted in the work, the wire is severed by knives mounted in the lower ends of two carrying arms 41 and 43 both fulcrumed on a shaft 47 mounted in the machine frame. The knife carrying arms or holders 41 and 43 carry gears (not shown) which mesh with co-operating gears on the forward end of a shaft 49 (Fig. 1). Upon rocking movement of the shaft 49, the holders 41 and 43 are reciprocated toward and from each other to cause the cutting edges of the knives to sever successive lengths of wire in timed relation to the operation of the wire feeding mechanism. The shaft 49 is oscillated through connections to a cam wheel 50 pro-

vided with two outstanding toes, one of which is shown at 51, adapted to operate intermittently a lever 52 operatively connected to the shaft 49.

5 In the use of the machine, the shoe to be operated upon is mounted upon a horn 54 and clamped between the horn and an abutment indicated at 55. In order that each wire nail inserted in the work may correspond to the thickness of the work at the fastening location, the extent of feeding movement imparted to the wire feed lever 28 by the wire feeding cam 40 is automatically varied. This is effected by providing 10 the horn 54 with a laterally extending arm (not shown) to the outer end of which is attached a measuring rod or leg 56 (Fig. 3) projecting upwardly through a guide in the machine frame and adapted upon upward movement of said rod to engage and move upwardly a co-operating rod 58, the lower end of which is in line with, but normally spaced from, the upper end of the rod 56. The rod 58 has its upper end pivotally secured to the end of a rearwardly extending arm 59 of the wire feed lever 28. Whenever the horn is moved upwardly into work clamping position, the measuring rod 56 is correspondingly moved to engage and move 15 the co-operating rod 58, whereupon the wire feed lever 28 is adjusted in respect to its operating cam 40 according to the thickness of the work.

Each time after the wire has been inserted in the work and a nail cut off, the work is automatically fed by a feed wheel 60, geared to the outer end of a shaft 62. The opposite end of the shaft 62 carries loosely a toothed sleeve 64 adapted to be oscillated by a rack 66 (Fig. 3) on the lower end of one arm of a two-armed lever 68. The other arm 70 of this lever is adjustably connected to a lever 72, the upper arm of which lever carries a cam roll 74 traveling in a cam track in the cam 40. A pawl 76 on the sleeve 64 engages a ratchet 78 on the shaft 62 and operates to rotate the shaft 62 when the sleeve 64 is oscillated. Means (not shown) is provided to prevent backward or reverse rotation of the feed wheel 60 when the lever 68 is being returned to normal position under the influence of a spring-pressed plunger (not shown).

The parts thus far described conveniently may be, and, as shown, are, constructed substantially as described in the above-mentioned Letters Patent, No. 490,621.

The horn 54 is automatically depressed to permit the work to be fed by mechanism including a rod 80 arranged to slide vertically on the column 2 of the machine. The rod 80 is raised to depress the horn by a rod 82 having attached to it a carrier 84 provided with a toothed plate 86 engaging ratchet teeth on the upper end of the rod 80. The

rod 82 is operated by a lever 88 fulcrumed on the machine frame and having a cam roll riding in a groove in the cam wheel 50.

In the illustrated machine, the operation of the fastening inserting mechanism is suspended by stopping the operation of the wire feeding and wire cutting mechanisms and locking the horn in lowered position, substantially as described in Letters Patent No. 1,264,188 with reference to Letters Patent No. 691,354, granted Jan. 21, 1902, on an application of Louis A. Casgrain. The mechanism for suspending the operation of the fastening inserting mechanism comprises a treadle (not shown) connected by a treadle rod 90 (Fig. 3) to a lever 92 pivoted on the machine frame and carrying an upstanding spring blade 94 which engages a latch 96 carried by a lever (not shown) having a cam roll traveling in a cam track on the rear side of the cam 40 whereby the said lever and the latch 96 are continuously reciprocated. The latch 96 is provided with ears or lugs adapted upon upward movement of the latch to engage corresponding ears or lugs on a switch member 98, fulcrumed on the machine frame. A bar 100 connects the switch member 98 with a stop block 102 adapted upon movement of the bar 100 to the left to be positioned under a collar 104 on the rod 58 and thus to render the fastening inserting mechanism inoperative.

Upon movement of the treadle one way or the other, the latch 96 is swung correspondingly through the lever 92 and spring blade 94, depression of the treadle moving the lever 92 in a direction to allow the latch to turn the switch member 98 into position to restore operative connection between the wire feeding and cutting mechanisms and their operating cams, and return movement of the treadle to its normally raised position operating reversely through the lever 92 and spring blade 94 to force the switch member 98 into position to stop the operation of these mechanisms.

In the illustrated machine, as in the machine of said Letters Patent No. 490,621, the operating cam 40 for the wire feed mechanism, like the cam 50 for operating the wire cutting mechanism, is a double throw cam so constructed that during every revolution of the cam shaft 22 two operative movements of the wire feeding mechanism are effected. Means is provided for automatically and periodically swinging the lever 92 downwardly once in every revolution of the cam shaft 22, thus throwing over the latch 96 and setting the switch 98 to suspend the operation of the wire feeding mechanism once in every revolution of the cam shaft so that, when extra wide spacing is desired, every alternate wire feeding movement will be omitted automatically and, instead of

feeding and inserting two fastenings during each revolution of the cam shaft, the machine will insert one fastening only during each revolution of the cam shaft.

5 Inasmuch as the described means for periodically suspending the operation of the wire feeding mechanism is independent of, and does not interfere with, the operation of the work feeding mechanism, it will be seen that, whenever the said means is operative, the work will have imparted to it two feeding steps or movements between each two fastening inserting operations, thereby multiplying in the ratio of one to two the spacing capacity of the machine.

As shown, in order to permit the lever 92 to be swung downwardly independently of the treadle rod 90 the treadle rod has a pin and slot connection 106, 108 with a hollow rod 110, the upper end of which has a ball and socket connection 112 with the lever 92, and a spring 114 is seated in the bore of the rod 110. The means for thus automatically and periodically swinging the lever 92 to effect alternate suspensions of the operation of the wire feeding mechanism comprises a double-armed lever 116 pivoted on the machine frame on an extension of the shaft which carries the wire feed arm 31.

30 The lever 116 carries on its shorter arm a roll adapted to be engaged by an edge cam piece fitted on the wire feed operating cam 40 and operating to swing the lever 116 once in every revolution of the cam shaft 22, all as clearly exhibited in Letters Patent, No. 1,264,188. The other and longer arm of the double-armed lever 116 is pivotally connected to one end of a rod or plunger 124, the other end of which is arranged to be received in a recess 126 (Fig. 1) at one side of the lever 92. A spring 128 (Fig. 1) connected at one end to the machine frame and at the other end to the rod 124 acts both to force the rod 124 laterally in line with the recess 126 and also in the direction to maintain the roll on the lever 116 in contact with the cam 40. The spring 114 operates to restore the lever 92 to normal position after it has been moved by the rod 124. Located in supports in the machine frame at one side of the rod 124 is a rotatable shaft indicated at 129 (Fig. 2) having an offset portion 130 so located that rotation of the shaft 129 to the right (Fig. 2) displaces the rod 124 laterally against its spring 128 out of line with the recess 126 so that, the rod 124 in its subsequent reciprocations does not enter the recess 126.

60 In accordance with a feature of the invention, means is provided for facilitating the adjustment of the normal range of work feed of the machine. It frequently happens that the normal range of feeding movement of the work is desired to be varied during operation on a single piece of work, as when,

in the manufacture of certain classes of shoes, it is required that the sole attaching fastenings be inserted at a less distance apart in the shank portion of the shoe than in the forepart. In such cases, the use of the mechanism hereinbefore described to obtain wider spacing of the fastenings in the forepart of the shoe may not be entirely satisfactory in that it may be desired that the ratio of the spacing of the fastenings in the shank and forepart respectively shall be other than one to two. Moreover, when such mechanism is employed, two separate work feeding operations are performed between successive fastening inserting operations, thus retarding the insertion of the fastenings and reducing the output of the machine. Accordingly, the illustrated machine is provided with mechanism whereby the normal range of feed of the work may be varied at the will of the operator during the operation of the machine on a piece of work and in a ratio different from that obtained by suspending the operation of the fastening inserting mechanism. Preferably, also, the machine embodies improved means for controlling the devices by which the operation of the fastening inserting mechanism is suspended when it is desired to insert fastenings at distances apart outside the normal range of feed of the machine.

As shown, a bracket 132 is bolted on the column 2 of the machine at about the height of the operator's knee, and is formed with two horizontal axially-aligned and spaced-apart bearings 134 and 136 in which are rotatably mounted sleeves 138 and 140. The sleeves 138 and 140 have V-shaped notches 141 and 142 respectively cut in their adjacent ends, and at their opposite ends they are provided with laterally projecting arms 143 and 144 respectively. The arm 143, near the front of the machine, has a ball-end which engages a slot 146 in an arm of a two-armed lever 148 pivoted on the bracket 132 and having its other arm 150 extending towards the rear of the machine. The latter arm 150 is connected by a rod 152 to a lever 154 (Fig. 3) pivoted on a shaft 156 mounted in a laterally offset portion 158 of the shaft 160 on which the lever 72 is fulcrumed. The lever 154 has formed on it a gear segment 162 meshing with a rack 164 slidably mounted in a plate 166 bolted to and constituting a part of the cam-actuated lever 72. The point at which the gear segment 162 and rack 164 mesh is coincident with the center of the pivot-shaft 160 of the cam-actuated lever 72 so that swinging movement of the lever about its pivot does not move the rack 164 relatively to the lever or cause the teeth of the segment 162 and rack 164 to part company. Pivoted on the rack 164 is a block 170 which engages a slot 172 in the upper arm of the feed

lever 68. The arrangement is such that when the rod 152 is moved upwardly the block 170 is moved nearer to the center of the pivot shaft 47 of the feed lever 68 and 5 away from the center of the pivot-shaft 160 of the cam actuated lever 72, with the result that the range of feeding movement of the work is increased.

The arm 143 on the sleeve 138 has an upwardly extending lug 178 against which 10 bears a spring-plunger 180, mounted in a boss on the bracket 132. The arm 144 on the sleeve 140 in the rear bearing 136, is connected by a rod 182 to an arm 183 on the 15 shaft 129. The arm 144 also has an upwardly extending lug 184 engaged by a spring-plunger 186 mounted in a boss on the bracket 132, which returns the arm 144, after it has been actuated, into position 20 against a stop (not shown) formed on the bracket 132. Passing through the two sleeves 138 and 140 is a shaft 188 which has pinned to it two collars 190 and 192, the inner faces of which bear against the arms 25 143 and 144 and hold them in position against the ends of the bearings 134 and 136, thus preventing the sleeves from moving endwise in the bearings.

The shaft 188 has fixed to it at its forward end a knee-lever 194 by which the shaft may be oscillated. Slidably mounted on the shaft between the inner ends of the sleeves 138 and 140 is a member 196 having V-shaped tongues 198 at each end adapted 30 selectively to enter the V-shaped notches 141 and 142 in the sleeves 138 and 140 respectively. The member 196 is keyed at 200 to the shaft 188 to prevent its rotation on the shaft but so as to allow it to slide along 35 the shaft. A hand-piece 202 projects upwardly from the member 196 for manipulation by the operator to move it along the shaft 188 to engage the tongues 198 with the notches in the sleeves, and a spring- 40 plunger 204 mounted in the member enters 45 one or the other of two recesses 206 in the shaft 188 to position the member when the tongues 198 are in engagement with the notches.

The arm 150 of the lever 148 at its rear end moves in a path adjacent to and in substantial parallelism with a vertical face 208 formed on the bracket 132 and provided with openings to receive pins 210 which 50 limit the up and down movements of the lever 148 and thereby determine the normal ranges of feed of the work. The openings are spaced to produce different amounts of work-feed. As shown, the lowest opening in the face corresponds to $\frac{5}{16}$ " of feed 55 movement and the highest hole to $\frac{3}{4}$ " or $\frac{13}{16}$ " of feed movement. The openings between the two limits are arranged to give work feeding movements varying by sixteenths of an inch. Two series of openings

are provided in the face, one series for a pin above the lever to limit its upward movement and the other for a pin below the lever to limit its downward movement.

As an example of the operation of the above-described mechanism for controlling the feed of the work, it will be assumed that it is desired to insert fastenings in the shank portion of a shoe $\frac{3}{8}$ " apart and in the forepart of the shoe $\frac{9}{16}$ " apart. The member 70 75 196 will be moved along the shaft 188 until the tongue 198 at the front end of the member 196 engages the notch 141 in the sleeve 138, and a pin will be inserted in the lower hole in the face 208 which corresponds to 80 $\frac{3}{8}$ " of feed movement, a pin being also placed in the upper hole in the face 208 which corresponds to $\frac{9}{16}$ " of feed movement. When inserting fastenings in the shank portion of the shoe, the knee-lever 194 will not 85 be actuated, and the spring-plunger 180 will hold the arm 150 against the lower pin, in consequence of which fastenings will be inserted $\frac{3}{8}$ " apart. When the forepart of the shoe is reached, the knee-lever 194 will 90 be actuated, and the arm 150 held up against the other pin, so that fastenings will be inserted $\frac{9}{16}$ " apart. When the shank is again reached, the knee-lever 194 will be released, 95 and the arm 150 will be returned into engagement with the lower pin, after which fastenings will again be inserted $\frac{3}{8}$ " apart. When it is desired to insert fastenings at a greater distance apart than that which 100 comes within the normal range of feed of the machine; for example, when $\frac{7}{16}$ " and $\frac{7}{8}$ " spacings are used as the short and long spacings respectively, the member 196 will be moved along the shaft 188 until the tongue 198 on the member 196 engages the 105 notch 142 in the sleeve 140. The knee-lever 194 will not be actuated when inserting fastenings along the shank, but when the forepart is reached the knee-lever 194 will 110 be actuated to lower the rod 182 and, thereby, to turn the shaft 129 from the position shown in Fig. 1 to the position shown in Fig. 2, so as to cause the operation of the fastening inserting mechanism to be periodically suspended, so that the fastenings are 115 inserted twice as far apart as before, i. e., $\frac{7}{8}$ " in the case assumed. The knee-lever 194 is released when the shank of the shoe is again reached, allowing the rod 182 to be returned by the spring-plunger 186 and rendering the rod 124 inoperative on the lever 92.

This controlling mechanism is convenient for operation in the course of operation on a piece of work, i. e., while the operator is handling the work-piece, and is further so devised as to be capable of operation without interrupting the operation of the machine in any way, that is, it is capable of 125 operation while the work feed, wire feed 130

and wire cutting mechanisms continue in operation.

Having thus described my invention, what I claim as new and desire to secure by Letters Patent of the United States is:—

1. In a machine of the class described, means for inserting screw-threaded fastenings comprising a rotary spindle for screwing the fastenings into the work, means for feeding the work past the spindle to cause a row of fastenings to be inserted in the work, means adapted to be actuated by the operator during operation of the machine on a piece of work to vary the normal feed of the work from one range to another, and means carried by the machine for determining the ranges of feeding movement of the work.
2. In a machine of the class described, fastening inserting mechanism, means for feeding the work past the fastening inserting mechanism, a lever for controlling the extent of feeding movement of the feeding means, a stop for locating the lever to determine a range of feeding movement of the feeding means, a sleeve connected to the lever, a spring operable on the sleeve to maintain the lever in operative relation to the stop, a second stop, a shaft rotatably mounted in the sleeve, means for connecting the sleeve and shaft for common rotation against the opposition of the spring, and means for rotating the shaft to move the lever into operative relation to the second-mentioned stop.
3. In a machine of the class described, fastening inserting mechanism, means for feeding the work past the fastening inserting mechanism, a lever for controlling the extent of feeding movement of the feeding means, a bracket to which the lever is pivoted, a stop disposed for engagement with the lever for locating it to determine a range of feeding movement of the feeding means, a sleeve journaled in the bracket and having an arm connected to the lever, a lug on the sleeve, a spring pressed plunger mounted in the bracket and operable through said arm to maintain the lever in operative relation to the stop, a shaft journaled in the sleeve, means for connecting the sleeve and shaft for common rotation, and means for rotating the shaft to move the lever away from the stop, thereby to determine a different range of feeding movement of the feeding means.
4. In a machine of the class described, a work feeding device and operating connections for the device comprising members, one of which is mounted for swinging movement, means for coupling the swinging member to the other member including an element movable to change the point of connection of the members and thereby vary the feed of the work, and a gear acting at

the axis of swing of the swinging member for moving the element.

5. In a machine of the class described, a work feeding device and means for operating the device comprising a pair of swinging members, an element for coupling the members together, the element being movable to change the point of connection of the members and thereby vary the feed of the work, and gearing acting at the axis of swing of one of the members for moving the element.

6. In a machine of the class described, a work feeding device and means for operating the device comprising members, one of which is mounted for swinging movement, connections between the members including a rack movable slidably in the swinging member to change the point of connection of the members and thereby vary the feed of the work, and a gear for moving the rack.

7. In a machine of the class described, a frame, a work feeding device, means for operating the device comprising members, one of which is mounted for swinging movement on the frame, connections between the members including a rack movable slidably in the swinging member to vary the feed of the work, and a gear journaled on the machine frame and disposed for engagement with the rack so that swinging movement of the member does not change the position of the rack in the member or cause disengagement of the teeth of the gear and rack.

8. In a machine of the class described, fastening inserting mechanism, means for feeding the work past the fastening inserting mechanism intermediate between the insertion of the fastenings, mechanism for multiplying integrally the range of feeding movement of the work between successive fastening inserting operations, and other mechanism constructed for actuation by the operator during operation of the machine on a piece of work to vary the feed of the work in a different ratio.

9. In a machine of the class described, fastening inserting mechanism, means for feeding the work past the fastening inserting mechanism intermediate between the insertion of the fastening, mechanism for varying the feed of the work during operation of the machine on a piece of work between two determinate ranges of feeding movement of variable relation, and other mechanism for multiplying integrally the range of feeding movement of the work between successive fastening inserting operations.

10. In a machine of the class described, fastening inserting mechanism, means for feeding the work past the fastening inserting mechanism intermediate between the

115

105

110

120

125

130

- insertion of the fastenings, mechanism for varying the normal range of feed of the work, other mechanism for multiplying integrally the range of the feeding movement 5 of the work between successive fastening inserting operations, and a common operator-controlled actuator for controlling the two mechanisms.
11. In a machine of the class described, 10 fastening inserting mechanism, means for feeding the work past the fastening inserting mechanism, intermediate between the insertion of the fastenings, mechanism for varying the feed of the work between two 15 ranges of feeding movement of variable relation, other mechanism for multiplying integrally the range of the feeding movement of the work between successive fastening inserting operations, a common actuator for 20 controlling the two mechanism, and means for connecting the actuator selectively to the mechanisms.
12. In a machine of the class described, 25 fastening inserting mechanism, means for feeding the work past the fastening inserting mechanism, intermediate between the insertion of the fastenings, controlling means for the feeding means operable to cause the work to be fed through one predetermined 30 range of movement, an actuator, and means constructed for movement by the actuator to cause the work to be fed through either of two other predetermined and unequal ranges of movement between successive fas- 35 tening inserting operations.
13. In a machine of the class described, 40 fastening inserting mechanism, means for feeding the work past the fastening inserting mechanism intermediate between the in- 45 sertion of the fastenings, a movable member for controlling the range of movement of the work by the feeding means, stops for locating the member to determine unequal ranges of feeding movement of the 50 work, means for normally maintaining the member in operative relation to one of the stops, an actuator for moving the member into operative relation to the other of the stops to change the range of feeding move- 55 ment, and means constructed for movement by the actuator to cause the work to be fed between successive fastening inserting operations through a range of movement other than that determined by either of the stops.
14. In a machine of the class described, 60 fastening inserting mechanism, means for feeding the work past the fastening inserting mechanism intermediate between the 65 insertion of the fastenings, means for sus- 70 pending periodically the operation of the fastening inserting mechanism during the operation of the machine constructed and arranged to increase the amount of work feeding movement of the work feeding mechanism between successive fastening inserting operations, mechanism for varying the normal feed of the work, and common controlling means for the suspending means and said mechanism.
15. In a machine of the class described, 75 a frame, fastening inserting mechanism, means for feeding the work past the fastening inserting mechanism intermediate between the insertion of the fastenings, means for suspending periodically the operation of the fastening inserting mechanism during the operation of the machine constructed and arranged to increase the amount of work feeding movement of the 80 work feeding mechanism between successive fastening inserting operations, mechanism for varying the normal feed of the work, a plurality of sleeves journaled in the frame, means operatively connected with 85 one of the sleeves for controlling the suspending means, means operatively connected with the other sleeve for controlling the mechanism, a shaft extending through the sleeves, and a member mounted on the shaft 90 for selective engagement with the sleeves.
16. In a machine of the class described, 95 fastening inserting mechanism, means for feeding the work past the fastening inserting mechanism intermediate between the insertion of the fastenings, means for suspending periodically the operation of the fastening inserting mechanism during the operation of the machine constructed and arranged to increase the amount of work feeding movement of the work feeding mechanism between successive fastening inserting operations, means for rendering the suspending means normally inoperative, a 100 movable member for varying the normal feed of the work, stops for locating said member to determine unequal ranges of feeding movement of the work, means for normally maintaining the member in operative relation with one of the stops, an actuator, and a member movably mounted on the actuator for selectively moving the member into operative relation with the other stop, and rendering the suspending 105 means operative.
- In testimony whereof I have signed my name to this specification.
- JOSEPH GOULDBOURN.
